(57) CLAIM

The ornamental design for a home plate-shaped dish or plate, as shown and described.

DESCRIPTION

FIG. 1 is a top view of the dish or plate.

FIG. 2 is a right side view thereof. The left side view is a mirror image of the right side view of FIG. 2.

FIG. 3 is a bottom side view thereof.

FIG. 4 is a top side view thereof; and,

FIG. 5 is a bottom view thereof.

The dashed lines showing optional elements in FIGS. 1-5 are for illustrative purposes only and form no part of the claimed design.

1 Claim, 4 Drawing Sheets
